UNITED STATES PATENT OFFICE.

LEVI HAAS, OF CHESTER, PENNSYLVANIA.

RAILROAD-TIE.

SPECIFICATION forming part of Letters Patent No. 391,704, dated October 23, 1888.

Application filed February 16, 1888. Serial No. 264,172. (No model.)

To all whom it may concern:

Be it known that I, LEVI HAAS, a citizen of the United States of America, residing at Chester, in the county of Delaware and State of Pennsylvania, have invented certain new and useful Improvements in Railroad-Ties, of which the following is a specification, reference being had therein to the accompanying drawings.

10 This invention pertains to certain new and useful improvements in metallic railroad-ties, having for its object the production of a tie composed, preferably, of integral parts for locking and securing a rail in position and holding the same as against displacement by reason of contraction or expansion of the metal.

The invention consists in the peculiar construction and arrangement of parts, substantially as shown and described.

In the accompanying drawings, Figure 1 is a view in perspective of my improved tie. Fig. 2 is a plan view. Fig. 3 is a central longitudinal sectional view. Fig. 4 is an end view, and Fig. 5 is a detail perspective view, of one of the locking-arms with parts broken away.

Referring to the drawings, A designates my improved metallic tie, in the center of which is formed a groove or opening, a, by turning down flanges a', which hold the tie embedded in the earth. I have also shown a lip, a², projecting from the bottom of the tie, which is to be used for attaching the tie to beams of a trestle or bridge, suitable bolts being passed through apertures of said lip. From the vertical longitudinal sides of the tie A project upward extensions B B, from which are formed bent locking plates or arms b b, having extended ends b', as shown. In the center of the outer portions or thickness of these extensions B are formed rectangular grooves or openings b'', and from the lower portions of these openings project short horizontal extensions b² b², whereon the rail is designed to rest. In each locking plate or arm b, which forms the inner thickness of each extension B, is formed a

groove or recess, b³, of a shape corresponding to the flange of the rail.

After the rail is secured in position the 50 locking plates or arms b are forced against the inner surfaces of the outer thickness of the extensions B and lock the rail firmly in position, the extended ends b' of said plates or arms fitting snugly under the horizontal extensions b². 55 By this means the rail is firmly locked in position and is so tightly held that contraction or expansion of the parts will not ordinarily loosen the hold of the locking-plates, but should the same become loose a few taps with 60 a hammer on the locking-plates will again tighten the parts.

To provide additional support for the rail, I insert a block, C, between the sides of the tie, and hold the same by spikes, the heads of 65 which overhang the flange of the rail.

One of the many advantages of my invention is the dispensing with spikes for securing the rails in position, and by means of my invention the rails will be firmly held against 70 any liability of being deranged by contraction or expansion of the parts, and the same embodies many advantages in point of simplicity, durability, and general efficiency.

I claim as my invention—

1. A metallic railroad-tie having upwardly-projecting extensions, and locking plates or arms formed therewith for securing a rail, substantially as shown and described.

2. A metallic railroad-tie having recesses 8c formed in its sides, horizontal extensions projecting therefrom, and locking plates or arms, substantially as shown and described.

3. A metallic railroad-tie having recesses formed in its sides, and locking plates or arms 85 provided with extended ends for locking the rail in position, substantially as shown and described.

In testimony whereof I affix my signature in presence of two witnesses.

LEVI HAAS.
